UNITED STATES PATENT OFFICE.

MATTHEW ROBERT MOORE, OF INDIANAPOLIS, INDIANA.

FRAMING OF STEAM-ENGINES.

SPECIFICATION forming part of Letters Patent No. 535,714, dated March 12, 1895.

Application filed December 29, 1893. Renewed January 31, 1895. Serial No. 536,890. (No model.)

To all whom it may concern:

Be it known that I, MATTHEW ROBERT MOORE, a citizen of the United States, residing at Indianapolis, in the county of Marion 5 and State of Indiana, have invented a certain new and useful Improvement in the Framing of Steam-Engines, of which the following is a specification.

The improvement relates to an intermediate 10 part between the high and the low pressure cylinders in the class of engines known as tandem-compound. It can be applied to all styles of tandem-compound engines. It is more particularly adapted for the style of engine known as "Corliss," because in Corliss 15 engines the steam is discharged through a wide aperture at or near the lower side of one cylinder, and is received in a corresponding narrow aperture extending across the whole 20 upper side of the other cylinder. I will describe the invention as thus applied.

I have discovered that it is practicable to stiffly connect the cylinders and to maintain the connection without interfering with the 25 introduction and removal of the large low-pressure piston and low-pressure cylinder-head and that the same device may serve as a steam passage and a steam reservoir.

I provide a single rigid casting of a general 30 rectangular figure, which I term a "distance-piece," having two opposite sides accurately faced, and applied against correspondingly faced surfaces on the two cylinders and firmly bolted thereto. It serves two functions,—the 35 first, that of a distance-piece serving efficiently as a tie to hold the cylinders reliably together, and a strut to brace the cylinders reliably apart, thus preserving their proper relative distances and as a separate function, forming 40 a passage for the steam from the lower side of the high pressure cylinder, first upward each side of the extended piston-rod, and then horizontally so as to form a free and long passage from the high-pressure to the low-pressure 45 cylinder, and a sufficient reservoir in which to receive and treasure the successive exhausts from the high-pressure cylinder and to equalize the supply during the several intermittent periods of induction therefrom into 50 the low-pressure cylinder. The form allows conveniently for moving the cylinder-head and piston of the low-pressure cylinder axially

in the line of the piston-rod and laterally outward and inward to permit these parts to be removed and re-introduced, when necessary, 55 without disturbing either cylinder or the distance-piece.

The accompanying drawings form a part of this specification and represent what I consider the best means of carrying out the invention.

Figure 1 is a side elevation showing the relation of my distance piece to the other parts of the engine. The remaining figures are on a larger scale. Fig. 2 is an end elevation of 65 my distance piece as seen from the left in Fig. 1. Fig. 3 is a vertical section on the line 3—3 as seen from the right in Fig. 2. Fig. 4 is a vertical section on the line 4—4 as seen from the left in Fig. 3. Fig. 5 is a plan view. 70 Fig. 6 is a horizontal section on the line 6—6 in Fig. 4. Fig. 7 is an end elevation of a portion corresponding to Fig. 4, with the nuts removed.

Similar letters of reference indicate corresponding parts in all the figures where they appear.

A is a chambered side concentric except that the exterior is rectangular instead of circular, having a flat face presented against the 80 end of the high-pressure cylinder M, a liberal cylindrical space a properly inclosed in the center for the extended piston rod and for the partial cylinder head and stuffing box, and an aperture a' near the bottom which matches 85 to the discharge passage m therefrom. This part A, a, is a hollow case of cast iron or other suitable material, having an outer and an inner shell connected by a sufficient number of cast-in braces A', through which are passed 90 studs B screwed into the metal of the high-pressure cylinder extending through the inner face of the chamber and having nuts on their ends so as to form a rigid and tight junction. The provision a, in the center receives the casting M' which is nicely fitted 95 to and serves as the stuffing box for the high-pressure cylinder.

D is a chamber which occupies the whole upper portion of the casting, and is in free communication at one end with the chamber A, which I shall term concentric which brings the steam up from the exhaust of the high-pressure cylinder, and at the other end with

the induction passage of the low pressure cylinder W.

E is the bottom of my casting a strong, straight portion which may be a single web 5 extending across from the bottom of the chamber A to the low-pressure cylinder. G is the vertical face of my distance piece on the side opposite to the concentric chamber A. It is matched against a correspondingly finished 10 area on the adjacent end of the low-pressure cylinder W. A large circular aperture g is formed in this face of sufficient size to allow the insertion and removal of the head W' of the low-pressure cylinder. The studs X which 15 confine the head W' to the cylinder W are let partially into the metal on this face G of my distance-piece and partly into the head W'. The thickness of the head and of this portion of the distance-piece should coincide 20 exactly, so that nuts X' properly set on the studs will confine both. Further bolts or studs Y secure my distance-piece to the high-pressure cylinder M, and corresponding studs or bolts Z outside of the circular series X 25 serve to hold my distance-piece and the low-pressure cylinder W firmly in their correct relations when the nuts X' are removed for any repairs.

H is the piston-rod, and I and J are stuffing- 30 boxes of any ordinary or suitable construction, strongly and tightly secured. The glands in these stuffing-boxes are adjustable by reaching into the hollow interior of the distance-piece.

35 I provide for staying and strengthening the chamber A by the horizontal hollow braces A' through which the holding bolts extend and for staying the chamber D by longitudinal webs D', D', cast in its interior.

40 The hollow interiors of the chambers A and D may be formed by coring in the ordinary manner, the ordinary provisions being made for tightly covering the core-print holes.

K K, &c., are additional pieces of sheet 45 metal or other suitable material, secured to flanges on the surfaces of my chambers. The spaces between these pieces and the casting may contain simply air, or felt, or other suitable non-conductors, to clothe the chambers 50 and prevent the escape of heat.

Modifications may be made without departing from the principle or sacrificing the advantages of the invention. I can vary the height and breadth of the casting, and I can 55 apply a plate or other cover on one side or both sides of the distance-piece to prevent

the escape of heat through the circulation of air in the interior, such plates being, one or both, removed when necessary to obtain access.

60 I claim as my invention—

1. A distance-piece for tandem-compound steam-engines, having opposite faces A and G, longitudinal parts D and E connecting them above and below the piston-rod, with a sufficient aperture in the face G and in the interior and side to allow the low-pressure cylinder head W, and the low-pressure piston to be taken out and put in therethrough, as 65 herein specified.

70 2. A distance-piece for a tandem-compound steam-engine, having opposite faces A and G, longitudinal parts D and E connecting them above and below the piston-rod, with a sufficient aperture in the face G and in the interior and side to allow the low-pressure piston to be taken out and put in therethrough, and having recesses around the hole in the face G, in combination with the head W' of the low-pressure cylinder, having a flange correspondingly recessed, and with studs X set in the low-pressure cylinder, standing in such recesses, and with nuts X' pressing partly on the distance-piece and partly on the flange of the cylinder-head, all arranged to serve as 80 85 herein specified.

90 3. In a tandem-compound steam-engine, the combination with the high-pressure cylinder M and low-pressure cylinder W of a distance-piece in a single casting of rectangular figure fitted between and adapted to receive the crushing and rending strains directly as shown, and having a capacious chamber A, D, therein leading from the eduction passage m of the high-pressure cylinder upward on each side of the extended piston-rod and thence longitudinally to the induction passage w of the low-pressure cylinder arranged substantially as shown so as to perform the triple functions of a distance-piece, 95 a connecting pipe and a steam reservoir between the cylinders, all substantially as herein specified.

95 In testimony that I claim the invention above set forth I affix my signature in presence of two witnesses.

MATTHEW ROBERT MOORE.
